United States Patent

Des. 234,583
Patented Mar. 25, 1975

234,583

SIGNAL

Arnold Ehrlich, Mattapan, Mass., assignor to Insanity, Inc., Mattapan, Mass.

Filed Aug. 24, 1972, Ser. No. 283,554

Term of patent 3½ years

Int. Cl. D29—99; D20—03

U.S. Cl. D10—109

FIG. 1

FIG. 2

FIG. 3

FIG. 4

FIG. 5

FIG. 6

FIG. 1 is a view in front elevation of a signal, showing my new design in a closed position,

FIG. 2 is a rear view thereof,

FIG. 3 is a top plan view thereof,

FIG. 4 is a view in front elevation of the signal in an opened position on a reduced scale;

FIG. 5 is a rear perspective view thereof; and

FIG. 6 is a bottom plan view of the signal on the scale of FIG. 1 in an open position.

I claim:

The ornamental design for a signal, substantially as shown and described.
